(57) **CLAIM**

The ornamental design for a butterfly lamp, as shown and described.

DESCRIPTION

FIG. 1 is a front perspective view of a butterfly lamp, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged detail view of area 8 in FIG. 1. The broken lines in the drawings are for the purpose of illustrating the boundaries of the enlarged detail view and form no part of the claimed design.
